GROUND CLAMP HOLDING TOOL

Charles W. Hoffman, Lakewood, N. J.

Application October 29, 1945, Serial No. 625,422

1 Claim. (Cl. 29—284)

(Granted under the act of March 3, 1883, as amended April 30, 1928; 370 O. G. 757)

1

This invention relates in general to tools and in particular to a retaining tool for holding a bonding or ground clamp or the like in proper position while its fastening means, such as a bolt and nut is being applied.

The usual practice in assembling bonding or ground clamps is to spring the clamp so that it can be forced onto the member to which the ground is being made and then forcing the ends of the clamp together with one hand while inserting the fastening device, such as bolt and nut, with the other hand. This procedure has been found very awkward and to facilitate the assembly or installation of such ground clamps I have provided a tool which can be applied to the clamp to hold it in proper position for insertion of the fastening means, leaving both hands free for the latter operation of applying and tightening the bolt and nut.

The objects of my invention, therefore, are, first, to provide an assembling tool for bonding clamps and the like which will hold the clamp in suitable position for insertion of a fastening means.

Second, to provide an assembling tool for bonding clamps which will accommodate different sized clamps.

Third, to provide an assembling tool for bonding clamps and the like which will hold the clamp in suitable position for the reception of a fastening means and which will lie close to the member to which the bonding clamp is applied so as not to interfere with the insertion of the fastening means.

Further objects and advantages of this invention, as well as its construction, arrangement and operation, will be apparent from the following description and claim in connection with the accompanying drawing, in which

Figure 1 is a perspective of the tool of the present invention,

Figure 2 is a perspective of a bonding or ground clamp positioned where it is to be fastened, and

Figure 3 is a perspective showing the tool of the present invention in operation.

The tool 1 of the present invention is adapted to be used for holding the bonding or ground clamp 3 while it is being fastened by means of the bolt 7 and companion nut 9. Such clamps are commonly employed for making electrical ground connections, a pipe 2 being a common structure used for a ground connection. The clamp 3 is first sprung over the pipe 2 as illustrated in Figure 2, at some selected position along its length. Under conventional practice, the clamp 3 is provided with the ears 5 having holes

6 through which the bolt 7 is projected. Under prior-art practice the clamp 3 must be held in encircling engagement with the pipe 2 and with its holes 6 in coaxial alignment, and it must be so held opposed to its inherent resiliency with one hand while the bolt 7 is projected through the holes 6 with the other hand, the clamp being so held until the nut 9 is threaded onto the bolt. The manual operation is naturally awkward, and the awkwardness of the operation is magnified when an electrical terminal 8 is included in the electrical connection of the assembly. The device of the present invention makes the operation easy and less time consuming.

15 The device of the present invention comprises the piece 1 of rigid strip material. A slot 4a, 4b, 4c is provided in the piece 1 extending longitudinally thereof, and under preferred practice the piece is formed arcuate in the transverse direction. The disclosed arcuate structure inhibits bending of the tool under the strain applied to it transversely by the inherent resiliency of the clamp 3. The arcuate structure also conforms the piece 1 to the general contour of the clamp 3 and the 20 pipe 2, and the tool is thereby positionable well out of the way for the bolt 7 when it is projected through the holes 6 and the nut 9 when it is threaded thereon. Metal is a suitably rigid material for the piece 1, and strip metal can be readily formed to provide the desired arcuate contour. Also, strip metal is generally thin, enabling the 25 tool 1 to be positioned on the ears 5 away from the holes 6 where it will not interfere with applying the bolt 7 and nut 9.

30 Under preferred practice as shown, the lengthwise slot is stepped at 4a, 4b and 4c to provide different widths varying progressively lengthwise of the piece 1. The distance between ears 5 may vary within considerable limits in different installations, and the steps 4a, 4b and 4c enable a slot width to be selected that is found most suitable for a given assembly operation.

In using the assembling tool, bonding clamp 3 is slightly sprung so that it may be forced onto 35 the pipe or like member 2 which is being selected for a ground connection. The ears 5 are forced toward each other with one hand and the slot of the tool 1 is projected over the ears 5 with the preferred step 4a, 4b and 4c in engagement therewith to hold the holes 6 in alignment. The inherent resiliency of the bonding clamp 3 forces the ears outwardly to bear against the sides of the slot, and this holds the clamp 3 with its holes 40 6 in alignment for the bolt 7 to be projected through them. Both hands of the operator are 45 50 55

free to thread the nut 9 onto the bolt 7, and also to position the terminal 8 onto the bolt before the nut is applied. Tightening of the nut 9 releases the resilient engagement of the ears 5 with the sides of the slot of the tool 1, and when the fastening means has been securely drawn up, the assembling tool is readily removed.

It will be noted that the assembling tool is shaped to substantially fit the contour of the member to which the bonding clamp is being applied and will not interfere with the installation of the fastening means.

From the foregoing it will be apparent that I have provided a very simple tool which will greatly facilitate the installation of bonding clamps. These clamps are used in great numbers in airships and airplanes, and similar clamps are used for grounding purposes in electrical and telephone work. My assembling tool will be of value in all fields where ground clamps are used.

It is to be understood that various modifications and changes can be made in this invention without departing from the spirit and scope thereof as set forth in the appended claim.

The invention described herein may be manu-

factured and used by or for the Government of the United States of America for governmental purposes without the payment of any royalties thereon or therefor.

What is claimed is:

A tool for holding ground clamps or the like during their attachment and comprising a piece of thin strip material, a slot in the piece extending longitudinally thereof, the slot being stepped to provide different widths varying progressively lengthwise, the piece being formed arcuate in its transverse direction.

CHARLES WM. HOFFMAN.
